UNITED STATES PATENT OFFICE.

JOHN R. LANDIS, OF ST. LOUIS, MISSOURI, ASSIGNOR OF ONE-HALF TO FRANK H. STROTT, OF ST. LOUIS, MISSOURI.

BURGLARPROOF GRIP.

Application filed November 7, 1921. Serial No. 513,269.

To all whom it may concern:

Be it known that I, JOHN R. LANDIS, a citizen of the United States, and resident of the city of St. Louis and State of Missouri, 5 have invented certain new and useful Improvements in Burglarproof Grips, of which the following is a specification containing a full, clear, and exact description, reference being had to the accompanying drawings, 10 forming a part hereof.

My invention relates to improvements in burglar proof grips, and has for its primary object a steel lined grip for bank messengers and the like, which is adapted to be secured 15 to the person carrying the same.

A further object is to construct a burglar proof grip, which when attached or secured to the person carrying the same, cannot be opened and the contents of the grip removed.

20 In the drawings,

Fig. 1 is a side elevation of my device, showing the manner of attaching the same to the person carrying it.

Fig. 2 a vertical cross section of the grip.

25 Fig. 3 a plan view of the band by which the grip is secured to the person carrying it.

Fig. 4 an enlarged fragmental view, showing the manner of securing the grip and band together,

30 Fig. 5 a view of a modified form of securing means.

In the construction of my device I employ a grip having a covering of leather or the like 6, and a lining of steel 7. The steel lining 7 is hinged on its sides as at 8, so that the upper portions 9 can be opened as indicated by dotted lines in Fig. 2. To the portions 9 are secured handles 10. The grip is adapted to be locked by means of a lock 11.

40 In order to secure the grip to the person carrying the same, I make use of a flexible band 12, which is provided with a lining 13. This lining is either felt, or similar material and is for the purpose of preventing scratch-

45 ing or cutting of the flesh. The band has integral ears 14 and 15 struck from a body of metal, and also a slot 16 through which the ear 15 passes. Secured to the ear 14 is a securing means 17. This may be either a chain or cable. The free end of this chain or cable is adapted to pass through openings 18 formed adjacent the upper edge of the hinged sides 9. After being passed through the openings 18, the free end is secured by 50

55 means of a padlock 19, which padlock also

is secured through the ear 15, thus locking the band 12 around the wrist of the person carrying the bag.

In Fig. 5 I have shown a modified form of securing means which consists of bars 20 and 21. The bar 21 being secured to the ear 14 by means of a link 22. While the bar 20 is provided with a perforation or opening 25 which is adapted to be secured by means of the padlock 19, the bars 20 and 21 are 60 pivotally secured to a short bar 26. When employing this structure, the bar 26 is located on the inside of the grip when the device is locked to the person carrying it and prevents absolutely any possibility of 65 prying the hinged portion 9 apart, so as to give access to the contents of the bag when the wrist band 12 has been secured in position.

While I have shown my bag as lined with 70 a solid steel lining, I do not desire to limit myself to this precise construction, as the bag may be lined with a steel chained mail. The sole purpose of the lining being to prevent any possibility of access being had by 75 cutting the bag.

It is to be understood, of course, that the person carrying the bag does not carry keys to open the same. One key being kept at the place from where the messenger is sent 80 with the bag, the duplicate key being at his ultimate destination. This will preclude any possibility of a frame up between the bank messenger and others, or any possibility of using force to obtain the key from the messenger and thus get away with the bag.

Having fully described my invention, what I claim is:

1. A burglar proof grip comprising a leather casing having a steel lining, a wrist band, and a flexible connection secured to the wrist band and adapted to pass through a portion of the grip and be secured at its free end to the wrist band.

2. A burglar proof grip comprising a 95 grip having a steel lining, a wrist band, a flexible connection having one end secured to said wrist band, its free end adapted to pass through said grip, and means for simultaneously locking the wrist band and securing the free end of the flexible member thereto.

In testimony whereof, I have signed my name to this specification.

JOHN R. LANDIS.
